UNITED STATES PATENT OFFICE.

GEORGE J. BANCROFT, OF DENVER, COLORADO.

PROCESS OF SPLITTING MICA.

1,383,370.

Specification of Letters Patent. Patented July 5, 1921.

Application filed March 4, 1919. Serial No. 280,570.

To all whom it may concern:

Be it known that I, GEORGE J. BANCROFT, a citizen of the United States, residing at the city and county of Denver and State of Colorado, have invented certain new and useful Improvements in Processes of Splitting Mica; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates broadly and generally speaking to a process of disintegrating minerals by explosive force, but the use of the invention which I have more particularly in mind is for splitting crude mica. Mica splittings are leaves of mica about as thick as tissue paper. These leaves are very valuable as compared with the crude mica, the latter being worth about 1¢ per pound, while the leaves or mica splittings are worth 60¢ per pound. These splittings, so far as I am aware, are now made by hand. I have made splittings by exploding the mica with steam. I placed the mica in a closed vessel or container with water, and heated the same. 30 When the pressure was high, I suddenly opened one end of the vessel and the mica exploded into splittings. The active agent is the water between the leaves of the mica, which is in a condition of unstable equilibrium at the moment of release. It suddenly expands into steam, separating the leaves.

It is evident that the process is not limited to splitting mica, but may be employed for 40 the disintegration of other minerals. So far as I am aware, practically all of the present methods of disintegrating minerals or other hard substances may be classified under two general heads, namely, (first) by abrasion—a

45 simple example of which is the common file—and (second) by external pressure—a good example of which is the common stamp mill.

My present invention consists, as I believe, of a radically new principle, namely, the disintegration of minerals by an explosive force 50 within the substance of the material. This is not akin to an explosion of powder, which has been introduced in one particular and localized part of the material, but is an explosion which is introduced throughout every

portion of the material to be disintegrated. To be more specific, I have accomplished this by the following means:

I have built a machine consisting of a relatively large, bottle-shaped container, having 60 a steam-tight valve hinged to its nozzle and held in place during the pressure-generating part of the process by a releasable trigger. The material, as crude mica, to be exploded is first soaked in water until all the cleavage 65 planes are full of water. It is then introduced into the container. Then, in addition to the water which is in the material, there is added a sufficient additional amount to generate the steam which is required and to 70 leave a small excess besides. Then the steam-tight valve is closed and heat is applied to the container, which is made stationary by suitable anchorage. There is a steam gage at the rear extremity, or the end opposite the 75 mouth or neck of the container, which gage registers the steam pressure. When sufficient pressure has been attained to accomplish the disintegration of the particular material under treatment, the trigger is pulled and 80 the hinged valve released. At the time of the release of the closure valve, the moisture which is in the material is in a state of unequal equilibrium and as soon as the pressure is relieved it becomes steam, tearing the material to pieces and having a tendency to preserve the fiber of the material. In addition to the explosive action of the steam, there is a further rending action, particularly in the case of mica, due to the violence with which 85 the material is discharged through the air. This rending action serves to finish any disintegration which the explosion failed to accomplish. The process is particularly applicable to the disintegration of any material 90 in which it is desired to preserve the fiber of the material, as mica, asbestos, wood for wood pulp, etc.

In further explanation of the process, I will refer to the accompanying drawing, in 100 which is illustrated one form of apparatus which may be employed in carrying out or practising the same, though it must be understood that the invention is not limited to any particular mechanical construction, as 105 various forms of apparatus may be employed.

In the accompanying drawing:

Figure 1 is a side elevation of one form of apparatus.

Fig. 2 is a vertical, longitudinal section of the container, shown on a somewhat larger scale.

Fig. 3 is a rear end view of the container, 5 or a view looking in the direction of arrow 3, Fig. 2, shown on a still larger scale.

Fig. 4 is a front end view of the container, or a view looking in the direction of arrow 4, Fig. 2, showing the valve open.

10 The same reference characters indicate the same parts in all the views.

Let the numeral 5 designate the body of the container, which may be of any suitable strength that may be necessary in view of 15 the pressure required in carrying out the process. As shown in the drawing, the rear extremity of the container is threaded to receive a screw flange, 6, having a collar, 7. This extremity of the container is closed by 20 a disk 8, which is secured to the flange by suitable fastening devices, as bolts 9. Mounted on the head 8 of the container is a pressure gage 10, which is in communication with the chamber of the container by a 25 pipe, 12.

The opposite extremity, 13 or the nozzle of the container, is threaded to receive a screw flange 14, having a collar, 15. A valve cap 16 is provided with an integral bar 17, one 30 end of which is hingedly connected, as shown at 18, to a bolt, 19, mounted on the flange 14. The free end of the bar 17 extends slightly beyond the cap and is adapted to be engaged for locking purposes by a 35 trigger, 20, which is hingedly connected, as shown at 21, to a bolt 22, mounted on the flange 14. This trigger has an arm, 23, extending beyond the pivot or fulcrum and connected therewith is a pull rod or cable, 40 24, which may be utilized for releasing the trigger when it is desired to explode the contents of the container.

In Figs. 1 and 2, the container is shown in position for use, or closed.

45 In carrying out the process, the container is charged with a water-soaked material, as mica, and some additional water added, as heretofore explained. The nozzle of the container is then closed, the valve cap being seated in a circular groove, 25, of the flange, 14, the trigger serving to hold the valve in the closed position and to make the container air- and steam-tight.

Heat is then applied to the container by

the use of oil or gas burners, 26, suitably 55 connected with a supply pipe, 27, and the heating of the container is continued until the gage indicates that the desired pressure is attained. The trigger will then be actuated to release the valve, which will fly open 60 or assume the position shown in Fig. 4.

The sudden release of the pressure in the container results in the explosion, which disintegrates the material under treatment, or splits the crude mica into the thin leaves of 65 which the relatively thick pieces are composed, the force with which the material is driven against the air also contributing to the proper performance of the disintegrating, or mica-splitting function. 70

I claim:

1. The herein described disintegrating process, consisting in heating water-soaked material in a closed container until the desired pressure is attained, and opening the 75 container to release said pressure suddenly.

2. A process of treating material, as mica, asbestos, wood, etc., consisting in first soaking the material in water, placing the material containing free water thus soaked up 80 in a fluid-tight container, heating it until a considerable pressure is attained, and suddenly opening the container to release said pressure.

3. The herein described mica-splitting 85 process, consisting in soaking the crude mica in water, placing it while it contains free water thus soaked up in a fluid-tight container, subjecting the contents to heat to produce pressure, and suddenly opening the 90 container to release said pressure.

4. The herein described mica-splitting process, consisting in soaking crude mica in water, placing it in a fluid-tight container containing free water, subjecting the contents to heat in the presence of said free water until a considerable pressure is attained, and opening the container to the 95 atmosphere to release said pressure.

5. A process of treating material such as 100 mica, asbestos and wood, consisting in soaking the material in water, placing the soaked material in a fluid-tight container containing free water, heating the contents of the container to develop considerable pressure, 105 and suddenly releasing pressure.

In testimony whereof I affix my signature.
GEORGE J. BANCROFT.
